UNITED STATES PATENT OFFICE

CHARLES H. YORK, OF MOLINE, ILLINOIS.

RAILWAY-RAIL BRACE.

1,085,315.

Specification of Letters Patent. Patented Jan. 27, 1914.

Application filed May 26, 1913. Serial No. 770,005.

To all whom it may concern:

Be it known that I, CHARLES H. YORK, a citizen of the United States, residing at Moline, in the county of Rock Island, State 5 of Illinois, have invented certain new and useful Improvements in Railway-Rail Braces; and I do hereby declare the following to be a full, clear, and exact description of the invention, such as will enable others 10 skilled in the art to which it appertains to make and use the same.

This invention relates to improvements in railway rail braces.

The principal object of the invention is to 15 provide a simple brace which can be quickly and easily adjusted for application to either straight rails or curves.

Other objects and advantages will be apparent from the following description when 20 taken in connection with the accompanying drawings.

In the drawings: Figure 1 is a plan view of my rail brace as applied to straight rails. Fig. 2 is a plan view of my invention as applied to a curve. Fig. 3 is a vertical transverse sectional view on the line 3—3 of Fig. 1. Fig. 4 is an enlarged plan view of the plate 18 and portions of the bars 11.

Referring particularly to the accompanying drawings, and especially Figs. 1 and 3, 30 10 represents the straight rails of a railway, to which my invention is applied. Extending from one of the rails are the bars 11, the outer end of each of which is bent to 35 brace the base of the rail, as clearly shown at 12. Slidably and adjustably mounted on each of the bars 11, for engagement with the base on the other side of the rail, is a clamp 13, this clamp being held by the bolts 14 and nuts 15. The opposite end of each of 40 the bars 11 is offset as indicated at 16, these ends being apertured to receive the vertical bolt 17. A plate 18 has its inner end disposed between the offset ends of the bars 11, 45 this end being apertured to receive the bolt 17 therethrough, so that the inner ends of

said bars are pivotally connected to the plate. The outer end of the plate 18 has a vertical extension 19, this extension carrying a set screw 20 which is adapted to bear 50 against the block 21 disposed between the said projection and the web of the rail, this block having a downturned portion 22 for engagement between the edge of the base of the rail and the projection 19. A clamp 23 55 is adjustably mounted on the plate 18 by means of the bolts 24 for engagement with the base of the rail on the side opposite the block 21.

As shown in Fig. 1, the device is used on 60 straight rails, but when it is desired to use the same on a curve, as seen in Fig. 2, the arms or bars 11 can readily accommodate themselves to curves of various degrees by virtue of their pivotal connection with the 65 plate 18. It will also be noted that the projection 19 and the attached clamp 23 engage one rail at a point directly opposite the joint of the opposite rail, the clamps of the arms or bars 11 engaging the second rail on each 70 side of the joint.

Attention is particularly directed to the fact that by virtue of the pivotal connection between the bars 11 and the plate 18, the said brace can be quickly and easily adjusted 75 to the rails of railways of different gages, and also to curves of different degrees.

What is claimed is:

In a rail brace, a member carrying a 80 clamp for engagement with one rail of a railway, bars pivotally connected to each other and to the said member and extending toward the opposite rail, and clamps carried by the said bars for engagement with the said opposite rail. 85

In testimony whereof, I affix my signature, in the presence of two witnesses.

CHARLES H. YORK.

Witnesses:

JOSEPH W. YORK,
HARRY RHINEHART.
